(57) **CLAIM**

The ornamental design of a front bumper for automobiles, as shown and described.

DESCRIPTION

FIG. 1 is a front view of the front bumper for automobiles showing my new design;

FIG. 2 is a top plan view thereof;

FIG. 3 is a bottom plan view thereof;

FIG. 4 is a right side view thereof;

FIG. 5 is a top, front and left side perspective view thereof; and,

FIG. 6 is a top, rear and right side perspective view thereof. The broken lines illustrate environmental structure only and form no part of the claimed design.
